(54) **SILK, WINDING, GIMP OR CORD**

(76) Inventor: **Adam Brooks**

D. W. Clancy & D. Brooks

The State wills referred to in this Specification consist of a part of the same containing a description in the words of the said A. of claim Brooks himself of his invention in the machine for knitting. Knitting or Crochet. To all to whom these presents shall come: Be it known that I, William Brooks of Gloucester in the County of Plymouth and State of Massachusetts have invented and & useful improvement to a Crochet machine for knitting Knits or Crochets which in its operations avoids the risk of whatever thread the cord is covered with after it is twisted which had formerly to be done before it was applied to the machine. Claiming the invention and application of spindle and fixed Number A. in such a way as to make the ~~twist~~ ^{obligatory} by the movement of the machine before the cord is covered. The old machine was so fixed that the operator had to vary the cord so as to lay it on the work after it was crocheted, equal by twisting a dozen turns and would require constant attention. I have invented and applied a new motion B. which lays the cord as given on equal the length of the work. The old spindle were made round where the work was put on except near the point which was square and made them inconvenient on account of not holding the work properly. I have made a slot on the spindle that holds the work (by means of an iron not in the end of the slot) in a firm and durable manner. The old machine had one small slot that contained the silk or thread to twist around the cord. I have invented and applied five or more slots on the wheel C. round the tube or spindle, thereby enabling the operator to perform more double the work in the same time and labor and also by having two or more colors on the different spools to make

make the groups of different regular columns at the same time if required. It has also a cover and a plumb weight, and rollers. Instead of (which may be weighted by a stopper or cork or by a beam with weights suspended from the cork) for the cork to pass around after being twisted, in order to make the cork sufficiently tight, its cover is well raised also to hinder it from being twisted. Please notice however that cork when passing round, from left to right,

will turn to the right. Month 12 to 136. Adams, Corks Wings.
